UNITED STATES PATENT OFFICE.

GEORGE D. FRAUNFELDER, OF EASTON, PENNSYLVANIA, ASSIGNOR TO EASTON CAR & CONSTRUCTION COMPANY, OF EASTON, PENNSYLVANIA, A CORPORATION OF PENNSYLVANIA.

BOX-GIRDER CONSTRUCTION FOR CAR BODIES.

Original application filed April 25, 1925, Serial No. 25,866, now Patent No. 1,609,807, dated December 7, 1926. Divided and this application filed November 9, 1926. Serial No. 147,232.

The present invention relates to dump cars in general and principally to that class of cars used in connection with quarry operations. All quarry cars when used for steam shovel service are subjected to tremendous shocks and strains. The load from the shovel dipper consists of large size stone and is usually discharged while the dipper is suspended high above the car body. Further, this load is very frequently dropped on the side and top edges of the body instead of on the bottom, and in quarry car construction, the car must be sufficiently rigid to prevent its being accidentally dumped or derailed from the force of such blows, either while being loaded or during transportation.

The upper longitudinally extending reinforcing edges of the usual constructions in cars of this type are readily bent upon receiving a severe blow or shock thereby totally distorting the car as a unit by reason of its being thrown out of alignment.

The object of my invention therefore may be briefly summarized as consisting of a novel reinforcing means for these longitudinally extending edges of box girder construction. In this construction the load is distributed uniformly thereby transferring any sudden blow or shock directly onto the side plates, thence to the subframe and continuing to the underframe of the car without distortion to the edge. The scope of my invention extends to whatever construction may be defined by or included within the terms or language of the appended claims.

This application is a division of my application for car units, filed April 25, 1925, bearing Serial No. 25,866, and now Patent No. 1,609,807, dated Dec. 7, 1926.

40 In the drawings:

Figure 1 is a side elevation of the portion of a dump car;

Figure 2 is a detail sectional view taken on the line 2—2 of Figure 1, and

45 Figures 3 and 4 are similar views of somewhat different embodiments of the box girder constructions.

My invention in the form or embodiments shown in the drawings and briefly described 50 comprises a main frame, 10, a car body, 11, and a reinforced outer edge or box girder indicated, generally, as at 12.

The car bottom, 11, is provided with a flat bottom, 13, and upwardly and outwardly diverging bottom portions or side plates, 14, terminating at their outer edges in right angular bent portions or ledges, 15, as is clearly illustrated in Figures 1 and 2. To further reinforce these outer ledges or bent portions, 15, I employ a plurality of I beams, 16, which are extended entirely across the bottom, 13, and conforms to the contour of the side plates, 14, of the bottom, 11. These supporting I beams, 16, are suitably riveted to the bottom, 13, and sides, 14, by means of the rivets, 17. The spacing of the supporting beams, 16, lengthwise of the car body, 11, of course depends upon the design of the particular car so as to provide a very rigid construction.

To further reinforce the outer ledges or bent portions, 15, I provide what might be termed a box-girder construction and is accomplished by means of an angular plate or strip, 18, extending lengthwise of the car body, 11. This strip, 18, is spaced apart from the plate or bottom, 14, the distance of the supporting I beams, 16, to which it is securely riveted as indicated at 19.

In the embodiment of my invention as illustrated in Figures 1 and 2, I employ an angle member, 20, which, of course, is provided with the leg, 18, extending parallel with the side plate, 14, and the member, 21, which is securely riveted to the right angular bent portion, 15 by means of the rivets, 22. In this embodiment of my invention, reinforced end or box-girder, 12, consists of a pair of relatively spaced parallel members and a pair of transversely extending and closely contacting members, 15 and 21.

In the form of my invention shown in Figure 3, the angularly bent end strip or ledge, 15^a, is further bent as indicated at 23, from which point it is extended downwardly and inwardly for a relatively short distance along the adjacent edge of the supporting beam, 16, to which it is securely riveted as indicated at 19^a. This downwardly and inwardly bent portion, 24, it will be noted, is of the same approximate length as the transversely extending portion, 12, and is, of course, spaced from the plate or bottom, 14, the same distance as the thickness of the

supporting beams, 16, so that the end of the supporting beams may be snugly fitted therebetween.

In the form of the box-girder construction illustrated in Figure 4, the side plate, 14, terminates at the outer end of the supporting beam, 16, to which it is, of course, riveted. In this instance I employ a pair of angle members, 25 and 26, whose spaced edges or legs, 27 and 28, are riveted to the side plate, 14, as shown at 29, and the opposite edges of the supporting beams, 16, also riveted as indicated at 30, whereas the portions or legs, 31, of the angles, 25 and 26, are riveted at 32. In this embodiment it will be noted that the transverse end of the box-girder is formed of two thicknesses of metal by reason of the pair of members or legs, 31, and in this respect is similar to the first described form of my invention.

This construction, it will now be readily seen, affords a very rigid and substantial support for the entire body of the car and effectually prevents any twisting, bulging or straining of the body with respect to the main frame support; all possibility of bulging or bowing down or out of any part of the side walls or box-girder construction being therefore eliminated.

30. What I claim is:

1. A reinforcing edge for metallic car bodies comprising, a plurality of transversely spaced supporting beams, each of said beams extending completely along the bottom and sides of the car, conforming to the contour thereof and secured thereto, the outer edge of said body being provided with a transverse and outwardly extending member integrally formed with respect thereto and extending the substantial distance of the thickness of said supporting beams and further provided with an integrally formed and downwardly bent portion and means for securing it to said supporting beams.

2. In a metallic car body, a reinforcing edge adapted to extend lengthwise of the car, and comprising, a plurality of vertically spaced supporting beams extending completely around the outer side of the body and conforming to the contour thereof, the upper end of said body being provided with a transverse and outwardly extending ledge integral with said upper end, the ledge extending transversely the substantial distance of the thickness of said supporting beams, said member being further provided with an integrally formed and backwardly bent angular portion, and means for securing said reinforcing ledge to the supporting beams. 45

50 3. A reinforcing edge for metallic car bodies comprising, a plurality of transversely extending and spaced supporting beams conforming to the contour of the body securely mounted to the outer side thereof, the outer edge of said body being provided with an 60 outwardly extending and right angular ledge, said ledge being integrally formed with respect to the adjacent portion of the car body, the transverse length of the ledge being substantially the same distance as the 70 thickness of the supporting beams, said right angular ledge being further provided with an integrally formed and backwardly extending right angular leg adapted to bear against the adjacent portion of said supporting 75 beams, and means for securing the leg to said supporting means.

4. A reinforcing edge for metallic car bodies comprising, a plurality of vertically spaced and transversely extending supporting beams secured to the outer side of the body and conforming to the contour thereof, and a substantially U-shaped reinforcing edge extending lengthwise of the body adapted to snugly fit a portion of the ends of 80 85 said supporting beams and riveted thereto.

GEO. D. FRAUNFELDER.
